UNITED STATES PATENT OFFICE.

PEDER ANDERSEN FISKER, OF COPENHAGEN, DENMARK, ASSIGNOR TO M/SRS. FISKER & NIELSEN A/S, OF COPENHAGEN, DENMARK.

VACUUM CLEANER.

Application filed March 22, 1922. Serial No. 545,648.

To all whom it may concern:

Be it known that I, PEDER ANDERSEN FISKER, subject of the Kingdom of Denmark, and residing at Copenhagen, Denmark, have 5 invented certain new and useful Improvements in Vacuum Cleaners, of which the following is a specification.

The present invention relates to an improvement in vacuum cleaners, especially 10 the small, easily transportable vacuum cleaners held by the hands during the cleaning and in which the suction nozzle is located on the vacuum cleaner proper. The present invention deals particularly with 15 the construction of the vacuum cleaner housing or casing. The complete casing of the vacuum cleaner comprises two main chambers, detachably connected with each other and one of which chambers forms a 20 filter chamber solely, and completely encloses the filter, while the other chamber forms a machine chamber containing the motor and the fan. The machine chamber is divided into two parts by means of an 25 intermediate plate which plate extends between the two separate portions of the propeller. In this manner one portion of the fan is located in one of the parts of the machine chamber, while the other portion of 30 the fan is located in the other chamber. The machine chamber has the handle of the machine pivoted to it at one end, while the other end is detachably connected to the filter chamber. A further advantage secured 35 by this construction is that both bearings of the motor and fan shaft are readily accessible because of their being located at the extreme ends of the shaft and further forming parts of the upper and lower walls 40 of the machine chamber. Because of the fan of the vacuum cleaner being located between the lower bearing and the rotor of the motor the construction of the vacuum cleaner may be much simpler than has been 45 heretofore the case.

In the drawing are represented all details necessary for the understanding of the invention.

Fig. 1 is a side elevation of the entire 50 vacuum cleaner;

Fig. 2 a horizontal central section of the same;

Fig. 3 an upper end elevation of the vacuum cleaner;

Fig. 4 is a detail of Fig. 2 on an enlarged 55 scale;

Fig. 5 is a detail showing the filter holding means.

The vacuum cleaner which is usually cigar or torpedo-shaped consists of two portions, 60 viz, the housing 1 containing the suction fan and the motor, and the conical portion 2 containing the filter. As shown in Fig. 2 the housing 1 consists of two portions, a lower 3 and an upper 4 held together by 65 screws 5 or the like. The bearings of the rotary shaft are located at the upper and lower wall of the housing and according to the invention the lower bearing 6 is located at the outside of the lower wall of the 70 housing, so that the bearing is easily accessible and simultaneously the construction of the entire housing 1 is made much smaller than when the lower bearing is located between the fan and the motor, as is the case 75 in prior constructions.

In the constructional form shown in Figs. 2 and 4 the intermediate plate 7, which leads inwardly the air leaving the first portion 8 of the fan so that it passes into the 80 second portion 9 of the fan near the shaft, is held in the housing 1 by having its edge pinched between the walls 3 and 4 forming the two chambers of the housing 1. The intermediate plate 7 may carry or be provided with ribs 10 carrying another plate 11 (the so-called hole plate), which serves also the purpose of leading the air in the correct manner in the housing so that it passes the same in the manner indicated by 90 the arrow in Fig. 2.

The conical portion 2 containing the filter 12 is detachably secured to the housing 1, by a pair of clamps 13 pivotally connected on the filter container 2 and so shaped that they may expand resiliently when turned in sidewardly over the screws 5 assembling the two portions of the housing 1. The clamps 13 consist of two branches connected by a cross piece 14 at the upper end of the 100 clamp and by a little bolt or pin 15 carrying a roller 16 which may be pressed on to the head of the screw 5 whereby the portion 2 is secured to the housing 1 by a resilient pressure arising from a small deformation 105 of the clamps 13 caused by the closing.

The filter 12 is located in known manner in the conical filter container 2 where it is

carried, according to the invention, by a special filter fastening, the form of which depends on that of the filter. In the constructional form shown (in Fig. 5) it consists of a perforated, substantially disc-shaped part 17, having a tubular or bar-shaped extension 18 supporting the lower portion of the filter. The disc-shaped portion 17 carries along its edge a rubber ring 19 making the joint between the housing 1 and the filter container 2 air-tight when the filter is in place. The portion 17 is so shaped that the edge of the filter may be easily fixed thereto, as by a cord 7' laid around the edge of the filter which surrounds the projection extending downwardly from the portion 17. As above-mentioned the lower end of the filter is held by a bar or a tube 18 terminating in a suitably shaped head to which the filter 12 is secured.

As indicated in Fig. 1 the vacuum cleaner is provided with a tubular handle 21 pivotally connected with the housing 1 so that it may be swung into a position along side of the housing of the vacuum cleaner during transport or when it is to be stored. As mentioned, the handle is in the form of a tube which serves in proper manner to receive the electrical connections not shown in the drawings. The handle may be secured in the various positions by a suitable butterfly or wing nut 22, Fig. 3.

The lower portion of the filter container 2 has formed on its end a cylindrical extension 23 on which the suction nozzle 24 is pivotally mounted.

Within the lower end of the filter chamber 2 is a check or flap valve 25 formed of a tube open at both ends and made of a thin piece of fabric or the like. When the vacuum cleaner is operating this tube will be sucked up so that it stands almost vertical and forms an open tube as shown in Fig. 2. As soon as this suction ceases this tube will collapse owing to the more or less vertical position of the vacuum cleaner, and in collapsing it will close the lower end of the container 2 so that the dust therein is prevented from falling out.

The constructional details shown and described may obviously be varied without departing from the principle of the invention.

Claims:

1. An improvement in vacuum cleaners of that kind which are held by the hands

during the cleaning, comprising a filter chamber and a machine chamber, a filter completely contained in the filter chamber, 60 an intermediate plate in the machine chamber dividing said chamber into two compartments the joint between the two compartments of the machine chamber being along the edge of the intermediate plate, 65 peripherally located means securing the two compartments to each other, a motor in one compartment of the machine chamber, a suction fan in said compartment in axial alignment therewith, a second axially 70 aligned fan in the other compartment of the machine chamber, and detachable connecting means for securing the filter chamber to the machine chamber which connecting means are held in position by the peripherally located securing means between the two compartments of the machine chamber.

2. An improvement in vacuum cleaners as set forth in claim 1, wherein the intermediate plate is secured between the two compartments of the machine chamber by having its edge pinched between the edges of the walls of said two compartments.

3. An improvement in vacuum cleaners as set forth in claim 1, wherein the detachable connecting means for securing the filter chamber to the machine chamber consist of resilient deformable clamps which are held in securing position by being stretched over 90 the peripherally located securing means which secure the two compartments of the machine chamber together.

4. An improvement in vacuum cleaners of that kind which are held by the hands 95 during the cleaning comprising a filter chamber and a machine chamber, means for detachably connecting the two chambers, a filter completely contained in the filter chamber said filter chamber being provided 100 with a cylindrical extension for the attachment of a nozzle, an intermediate plate dividing the machine chamber into two compartments, a motor and an axially aligned suction fan in the other compartment, peripherally located means maintaining the intermediate plate in position and securing the two compartments to each other, said compartments joining each other along the edge of the intermediate plate.

In testimony whereof I affix my signature.

PEDER ANDERSEN FISKER.
